CLAIM

The ornamental design for a tumbler as shown and described.

DESCRIPTION

FIG. 1 is a first perspective view of a first embodiment of a tumbler, showing our new design;

FIG. 2 is a second perspective view of FIG. 1;

FIG. 3 is a front view of FIG. 1;

FIG. 4 is a rear view of FIG. 1;

FIG. 5 is a first side view of FIG. 1;

FIG. 6 is a second side view of FIG. 1;

FIG. 7 is a top view of FIG. 1;

FIG. 8 is a bottom view of FIG. 1;

FIG. 9 is a first perspective view of a second embodiment of a tumbler;

FIG. 10 is a second perspective view of FIG. 9;

FIG. 11 is a front view of FIG. 9;

FIG. 12 is a rear view of FIG. 9;

FIG. 13 is a first side view of FIG. 9;

FIG. 14 is a second side view of FIG. 9;

FIG. 15 is a top view of FIG. 9; and,

FIG. 16 is a bottom view of FIG. 9.

The broken lines shown in the drawings are included for the purpose of illustrating the unclaimed boundary or unclaimed portions of a tumbler. The broken lines form no part of the claimed design.

1 Claim, 16 Drawing Sheets
